STATION SELECTOR FOR RADIORECEIVERS

Fritz Koch, Dresden, Germany

Application November 2, 1927, Serial No. 230,646
In Germany September 24, 1927

23 Claims. (Cl. 250—40)

This invention relates to selective wireless receiving apparatus employing one or more oscillatory circuits tuned by means of variable condensers, and the object of the invention is to provide a new and improved construction and arrangement of parts in a condenser which will enable a number of condenser settings to be made for tuning a circuit into resonance with a number of transmitting stations operating at predetermined wave lengths, and such settings to be preserved after having been once made, so as to be instantly available for tuning in any one of the stations represented by the settings by a simple switching operation, i. e., without "fishing" or searching.

The invention consists essentially in the employment of several adjustable condensers mounted in one assemblage in combination with means for selecting one of the number for connection to the receiving apparatus so as to form part of the tuned receiving circuit.

Two embodiments of the invention will be hereinafter described, by way of example, with reference to the accompanying drawing, said embodiments being shown in top elevation, partly in section, the one in Fig. 1, the other in Fig. 2, and also showing diagrammatically a circuit to be tuned thereby.

The embodiment shown in Fig. 1 will be first described.

As mentioned above the condenser comprises several adjustable condensers, five being shown in the present instance and denoted A, B, C, D, E, respectively. These are mounted in a frame *a*, made of insulating material. A shaft *b* journaled in this frame serves as a current conductor. The shaft *b* carries a milled knob *c* on one end and its other end rests on a center pivot *d*. Each of these several condensers comprises a stationary member consisting of a set of stator plates *e* fixed on the frame *a* and an adjustable member consisting of a set of rotor plates *f* mounted on the shaft *b*. The sets of plates *e* of the respective condenser units A, B, C, D, E are insulated from one another by insulating partitions or disks *g* and are sufficiently spaced to avoid undesirable reactions or intercapacity effects. Each set of rotor plates *f* on the shaft *b*, is loose on said shaft and adapted to be coupled to or uncoupled from said shaft *b* independently of the other sets, this being effected by means of a clamping or friction means, constructed in any convenient manner, such, for example, as a set-screw *h*.

The arrangement shown in Fig. 1 is intended

for five different capacity settings; it might, however, be constructed for more or less settings than five. The movable member of each condenser unit may be frictionally or otherwise held in its adjusted position and each unit when once adjusted for tuning the circuit to a given wave length is intended to remain so adjusted as long as it is desired to have such unit adjusted for tuning in such particular station. When, however, an alteration in any condenser setting or adjustment is desired, it can be made at any time. The adjustment of each condenser is effected by coupling its hub, by tightening the set-screw *h*, to the shaft *b* whereupon, by rotating shaft *b*, the rotor *f* may be adjusted with relation to the stator *e* until the desired capacity value is obtained. The screw *h* is then loosened so that shaft *b* is uncoupled from the rotor of the condenser unit which has been set or adjusted and which will remain so set or adjusted, and without being affected by any subsequent turning movements of shaft *b*, unless and until it is again connected to the shaft by its set-screw *h*.

This condenser is mounted in a radio apparatus, as shown, for example, in a receiver *R*, for tuning the same into resonance with the stations selected. A switch *k*, which is shown as a lever-switch, but might be a push-button-switch, serves for selectively connecting any one of the conductors *i*, *i'*, *i''*, *i'''*, *i⁴* from the stators of the condenser units with the receiving circuit, while a conductor *i⁵* connects the shaft *b*, and consequently all the rotors of the condenser units, in common with said circuit.

Fig. 2 shows another form of construction by way of example, in which the condenser units A', B', C', D', E' are complete in themselves, i. e., separate devices being provided for adjusting each set of rotor plates. As shown, the casing is sub-divided into a series of compartments by partitions *l* of insulating material carried by rods or bars *m*. Each set of stator plates *e'* is fixed on a partition *l*, and the coacting set of rotor plates *f'* are carried by a shaft pivotally mounted in said partition. Levers *o*, one for each set of plates *f'*, have projecting handles *p*, and one of these levers *o* is provided for adjusting the rotor plates of all the condenser units except the unit A', a knob or dial *r* being provided on the shaft of the rotor plates of unit A' for adjusting the rotor plates of this unit. As in the construction shown in Fig. 1 the movable members of the adjusted units may be frictionally or otherwise held in adjusted position, and conductors from the rotors of all

the units are provided for connecting the same with one side of the oscillation circuit to be tuned, while a switch lever q serves for operating a switch arm or member q' connecting any one of a series of switch points i^x , i^{1x} , i^{2x} , i^{3x} , i^{4x} forming the terminals of conductors leading from the sets of stator plates of the respective condenser units with the other side of said circuit. The use of knob or dial r for tuning condenser unit A' permits this condenser unit to be adjusted by a conveniently arranged adjusting element which is mounted on the outer end of the shaft of the unit A' which is extended through an opening s in the front panel P to the outside of the receiver casing, for the use of the unit A' as a general purpose condenser, that is, for tuning the receiver to any station it is capable of receiving, while the levers o may be arranged on the inside of the panel P , if desired, as these are used to set units B' , C' , D' , E' to tune in certain stations and, therefore, need be operated only when changing the setting of any of these latter-named units.

The switch lever q , as shown, is mounted to rotate on the shaft of the condenser unit A' on the outside of the panel and carries the switch arm q' which in turn carries the contact member q^2 which extends to the interior side of the panel through a slot q^3 in the panel in which it is movable through its working arc so as to sweep over the contacts i^x — i^{4x} to cut any of the pre-set condenser units B' — E' or the continuously variable condenser unit A' into or out of the radio circuit. The series of contacts i^x — i^{4x} are mounted on a switchboard or plate P' of insulating material arranged at the front of the condenser frame between the continuously variable condenser unit A' and the panel P . With this arrangement it will be seen that the individual condenser units B' — E' may be adjusted by means, namely, their adjusting or setting levers o located on the inside of the panel, to pre-set said condensers to proper values for pre-tuning the circuit to different selected working frequencies, while the condenser unit A' may be adjusted by means of its knob or dial r for independently tuning the circuit to any frequency throughout its entire frequency range or any desired part thereof. It will also be seen that the switch contact member q^2 is so arranged as to form with the contacts i^x — i^{4x} a selector switch the contact members of which are operably engageable on the inside of the panel while the movable member thereof, the contact member q^2 mentioned, is movable for operable engagement with its coating contacts i^x — i^{4x} by means located on the outside, i. e., the front, of the panel P . The switch arm q' is extended beyond the contact member q^2 which may cooperate with suitable indicator marks on or visible at the outer face of the panel so that the operator may tell at a glance the position to which the switch arm is movable to bring the contact member q^2 into engagement with any of the contacts i^x — i^{4x} , as well as to tell which contact of the series the contact member may be in engagement with at any particular time when the switch is in use.

I claim:—

1. A multi-unit variable radio condenser comprising a frame, a rotary shaft journaled on the frame, a plurality of independent condenser units, each consisting of relatively stationary and adjustable members respectively fixed to the frame and loosely mounted relative to the shaft,

means for independently coupling the adjustable members of the units to the shaft and uncoupling the same therefrom, whereby the adjustable members of the respective units may be adjusted by rotation of the shaft for pre-setting the units for tuning a radio circuit into resonance with transmitting stations of different frequencies, and switching means for selectively connecting any of said individual units with or disconnecting it from the radio circuit without disturbing the setting of the individual units.

2. A multi-unit variable radio condenser comprising a frame, a shaft journaled on the frame, a plurality of condenser units each comprising relatively stationary and adjustable members respectively supported by the frame and the shaft, the said adjustable members being normally loose relative to the shaft and adapted to be fixed thereto for adjustment thereby, whereby the movable members of the units may be independently adjusted for individually pre-setting the respective units for tuning a radio circuit into resonance with transmitting stations of different frequencies, means for independently connecting the movable members of the respective units to and disconnecting the same from the shaft, and switching means for selectively connecting any of said individual units with or disconnecting it from the radio circuit without disturbing the setting of the individual units.

3. In a radio tuner, a frame of insulated material, a gang of air condensers mounted in cascade on said frame, each comprising a stator and a rotor, partitions of insulated material on the frame disposed between and separating the individual condensers from each other, a single means for separately and independently adjusting the rotors of the respective condensers, whereby the condensers may be individually pre-set for tuning a radio circuit into resonance with a like number of individual transmitting stations operating on different wave lengths, and switching means operable to selectively connect any of the pre-set condenser units with a radio circuit.

4. A tuner for radio apparatus comprising a frame, a shaft journaled in the frame, a plurality of sets of stator elements on the frame, a plurality of sets of coating rotor elements loosely mounted relative to the shaft, coupling means whereby each set of rotor elements may be coupled to the shaft for adjustment thereby to a predetermined angular position and then released therefrom, whereby the rotors may be independently adjusted by the shaft for setting actions to tune a radio circuit to different frequencies, and switching means for connecting any of the sets of rotors and stators to a radio circuit.

5. A tuner for radio apparatus comprising a frame, a shaft journaled in the frame, a plurality of sets of stator elements on the frame, a plurality of sets of coating rotor elements loosely mounted relative to the shaft, coupling means whereby each set of rotor elements may be coupled to the shaft for adjustment thereby to a predetermined angular position and then released therefrom, whereby the rotor elements may be independently adjusted by the shaft for setting actions to tune a radio circuit to different frequencies, means for connecting the sets of stator elements to one side of a radio circuit, and a switch device for connecting the

- sets of rotor elements independently of one another to the other side of said radio circuit.
6. A tuner for radio apparatus comprising a frame of insulating material, partitions on the frame separating the same into spaces, a shaft journaled on the frame, a set of stator elements carried by the frame in each of said spaces, a set of rotor elements on the shaft in each of said spaces for coaction with the stator elements therein, the sets of rotor elements being loosely mounted relative to the shaft, means for independently connecting the same to the shaft, whereby the sets of rotor elements may be adjusted to different angular positions for coaction with the stator elements to tune a radio circuit to different frequencies, means for connecting all the stator elements to one side of a radio circuit, and a switch device for connecting the sets of rotor elements independently of one another to the other side of said circuit.
7. A tuner for radio circuits comprising a gang of tuning units, an adjusting element common to said units normally operably disconnected therefrom, means for separately coupling said adjusting element to each unit, whereby any unit of the gang may be adjusted independently of the other units, and means for selectively connecting any of the tuning units into a radio circuit.
8. A tuner for radio circuits comprising a gang of variable tuning condensers, an adjusting element common to the movable elements of the condensers normally operably disconnected therefrom, means for separately coupling said adjusting element to the movable elements of the condensers, whereby any condenser of the gang may be adjusted for tuning a radio circuit to a predetermined frequency independently of the other condensers, and means for selectively connecting any of the condensers into a radio circuit.
9. A tuner for radio circuits comprising a gang of tuning units, an adjusting element common to said units normally operably disconnected therefrom, means for separately coupling said adjusting element to each unit, whereby any unit of the gang may be adjusted independently of the other units, and a switch for independently and selectively connecting any of the tuning units of the gang with a radio circuit.
10. A tuner for radio circuits comprising a gang of variable tuning condensers, an adjusting element common to the movable elements of the condensers normally operably disconnected therefrom, means for separately coupling said adjusting element to the movable elements of the condensers, whereby any condenser of the gang may be adjusted for tuning a radio circuit to a predetermined frequency independently of the other condensers, and a switch for independently and selectively connecting any of the condensers of the gang with a radio circuit.
11. A tuner for radio circuits comprising a frame, a rotary shaft journaled on the frame, a plurality of condenser units carried by the frame each consisting of a stator and a rotor, the rotors of said units being normally operably disconnected from said shaft, coupling means for coupling each rotor to and uncoupling it from the shaft, whereby the rotors may be independently adjusted by the shaft to predetermined angular degrees with relation to their stators for setting said units for respectively tuning a radio circuit to different frequencies, and switching means for connecting any of the individual units into the radio circuit.
12. A tuner for radio circuits comprising an insulated frame, insulating partitions separating said frame into a plurality of spaces, a shaft journaled on the frame, a plurality of condenser units disposed in said spaces, each condenser unit consisting of a stator and a rotor, the rotors of said units being normally operably disconnected from said shaft, coupling means for coupling each rotor to and uncoupling it from the shaft, whereby the rotors may be independently adjusted by the shaft to predetermined angular degrees with relation to their stators for setting said units for respectively tuning a radio circuit to different frequencies, and switching means for connecting any of the individual units into the radio circuit.
13. A tuner for radio circuits comprising a plurality of tuning instruments embodying relatively stationary and movable elements, a rotatable shaft common to and normally operably disconnected from the movable elements of said instruments, coupling means whereby the movable elements of the instruments may be independently coupled to the shaft for adjustment thereby to a predetermined tuning position and then operably released therefrom, for setting said instruments for respectively tuning a radio circuit to different frequencies, and switching means for connecting any of the tuning instruments to the radio circuit.
14. In a radio tuner, a gang condenser comprising a frame, a series of unitary air condensers mounted in cascade on the frame and each embodying a stator and a rotor, a shaft common to the series of condensers, coupling means for connecting the shaft with the rotor of any of the condensers, whereby said rotor may be adjusted relatively to its stator independently of the rotors of the other condensers, and switching means for selectively cutting any of said condensers into or out of a radio circuit.
15. In a radio tuner, a panel, a tuning device comprising a gang of individual variable air condensers disposed on one side of the panel, each condenser embodying stator capacitor plates and rotor capacitor plates, an adjusting element common to said condensers and normally operably disconnected therefrom, said element having an operating portion disposed on the opposite side of the panel from the condensers, means for separately and independently connecting said adjusting element to the rotor capacitor plates of the respective individual condensers, whereby the condensers may be individually adjusted to different frequency settings, and a switch device including an operating element also disposed on the opposite side of the panel from the condensers for selectively connecting any of the condensers with and disconnecting the same from a radio circuit.
16. In a tuner for radio circuits, a tuning device comprising a plurality of individual variable air condensers each embodying a stator and a rotor, a single means normally operably disconnected from but having a cooperative coupling connection with the condenser rotors for separately and independently adjusting the rotors of the respective condensers with relation to their stators, whereby any condenser of the gang may be individually adjusted for tuning a radio circuit to a predetermined frequency independent of any other condenser of the gang, and a switch

device for cutting any of the condensers into or out of a radio circuit.

17. An electrical condenser comprising a plurality of variable condenser units, each independent of the others, one of said units being continuously variable and having an operating shaft, means associated with each of the other condenser units for independently adjusting said unit to vary its capacity, whereby said other units may be individually set for tuning a circuit when connected therewith into resonance with a corresponding number of stations of different frequencies, and a switch device including a movable member mounted concentric with the operating shaft of the continuously variable condenser unit for connecting any of the condenser units into a radio circuit independently of the others.

18. In a tuner for radio circuits, a plurality of separate and independent condenser units adjustable for pretuning a circuit to different working frequencies, means for independently adjusting said condenser units, a continuously variable condenser unit including a rotatable member having an adjusting shaft, switching means for selectively cutting said units into or out of the radio circuit including contacts arranged concentric with said adjusting shaft and a rotary contact member mounted coaxially with said shaft for engagement with said contacts, and operating members for independently shifting said contact member and the rotatable member of said continuously variable condenser.

19. In a tuner for radio circuits, a plurality of variable condenser units arranged one in rear of the other and each consisting of relatively fixed and adjustable capacitor members, means upon each condenser unit in rear of the first unit of the series for relatively adjusting the capacitor members thereof independently of the capacitor members of the other condenser units to vary the effective capacity of said unit, whereby said units may be pre-set to tune the circuit to different working frequencies, the said first unit of the series being continuously variable for tuning the circuit over a desired frequency range and having an operating shaft for adjusting the movable capacitor member thereof, means connected with the shaft of the first unit for operating the same, and switching means concentric with the shaft of the first unit for cutting said condensers into the circuit.

20. In a tuner for radio circuits, a gang condenser comprising a series of individual con-

denser units arranged one in rear of the other and each embodying a stator and a rotor, the rotor of one of the end units of the series having an adjusting shaft, means upon the rotor of each of the other units of the series extending outward radially with relation to its axis for adjusting said rotor to vary the capacity of the unit, a switchboard arranged adjacent to said end unit and in advance of which the adjusting shaft of said unit extends, switch contacts on the switchboard concentric with said shaft and connected with the respective condenser units, a rotary switch member mounted coaxially with said shaft and engageable with said contacts for selectively cutting the condenser units in or out of a radio circuit, and means uniting said units and switchboard in a unitary structure.

21. In a tuner for radio circuits, a gang condenser comprising a frame structure, a series of adjustable condenser units mounted on the frame structure, each unit being adjustable to vary its setting without varying the setting of any other unit, a switchboard carried by the frame structure, an additional variable condenser unit carried by the frame structure between the switchboard and said series of condenser units, said additional unit having an adjusting shaft extending in advance of the switchboard, a hollow shaft mounted on and rotatable about said adjusting shaft, an operating element for adjusting the adjusting shaft, switch contacts on the switchboard respectively connected with said units, and a switch connected with the hollow shaft and movable thereby for coaction with said contacts to selectively connect any of said units with a radio circuit.

22. In a tuner for radio circuits, a gang of variable condenser units, comprising a plurality of pretuning units with means for respectively presetting said units for selectively tuning a radio circuit to different working frequencies and a continuously variable unit adjustable without disturbing the setting of any of the aforesaid units for tuning the circuit throughout a desired frequency range, a control shaft operable for adjusting the continuously variable condenser unit, and switching means arranged at one end of the gang and comprising contacts concentric with said shaft and connected to the units of the gang, and a switch member mounted coaxially with said shaft and engageable with the contacts for selectively connecting the units of the gang with the circuit.
